Mar 1727

Elemir J. Ney, of Lowell, Mass.
Assignor to.

The Lowell Manufacturing Company.

Letters Patent No. 1727, dated Mar. 3. 1863.

The schedule referred to in these Letters Patent and making part of the same.

To all whom it may concern:

Be it known that I, Elemir J. Ney, of Lowell, in the County of Middlesex, and State of Massachusetts, now temporarily residing in New York, have originated and designed a new Pattern for carpets or other fabrics, of which the following is a full, clear and exact description, reference being had to the accompanying drawings, making part of this specification.

A, is a figure composed of small rosettes and lace work, resting on the ground 1. This ground is enclosed, successively, by the frame 2, band of sprigs 3, and cord and mottled work 4.

Fig. B, is similar, in form and surroundings, to fig A. C, and D, at the sides, when matched, form a large veined figure in the centre of which is a small rosette. This veined figure rests on the ground 5, which is enclosed by a frame, sprigs, cord and mottled work, similar to those enclosing the ground 1.

In the four corners are sections of figures, similar to C, and D. 6, 7, 8, and 9, are small diamond shaped figures, each composed of four small blocks. The set figure 10 occupies the centre of the drawing. The remainder of the design consists of a wavy ground work.

The colors employed for the different portions of the design, may be varied to suit the taste and wish of the manufacturer.

—Claim.—

What I claim as my invention, and desire to secure by letters patent, is the design or patent for carpets or other fabrics, herein set forth.

Witnesses.
